UNITED STATES PATENT OFFICE.

CHARLES KELLY, OF PASSAIC, NEW JERSEY.

DESIGN FOR AN ACETYLENE-GAS BICYCLE-LAMP.

SPECIFICATION forming part of Design No. 30,666, dated May 2, 1899.

Application filed April 7, 1899. Serial No. 712,181. Term of patent 7 years.

To all whom it may concern:

Be it known that I, CHARLES KELLY, of Passaic, in the county of Passaic and State of New Jersey, have invented and produced 5 a new and original Design for an Acetylene-Gas Bicycle-Lamp, of which the following is a full, clear, and exact specification.

Reference is to be had to the accompanying drawing, forming a part of this specification, 10 in which the figure is a side elevation of an acetylene-gas bicycle-lamp, showing my design.

The design in its entirety consists of a body A, having a base A' and a reduced neck portion A², crowned by a cap B, from the arched top of which rises centrally a screw C and from the rear end of which extends upward and outward a cylindrical portion D, covered by a cap E, the said body having opposite 20 lugs F and G, of which the lug G extends forward and terminates in the apex end of a parabolic reflector H, having its ornamental

base parallel with the vertical center of the body A and having its side embellished by an ornament I and cut facets and its rear top portion ornamented by a cylindrical portion J, rising vertically, with a cap K at the top, the lower rear portion of the reflector and the base A' appearing connected by an L-shaped pipe L, having a boss L' at the junction of 25 the pipe members, and a screw-head N appearing on the bottom of said boss.

The leading features of the design consist of the body A, the reflector supported from the body at the front thereof, and the pipe 30 connection between the reflector and the body.

I claim—

The design for an acetylene-gas bicycle-lamp herein shown and described.

CHARLES KELLY.
